RONALD G. SMITH, OF FAIRFIELD, CONNECTICUT

TOY RAILWAY SYSTEM

Application filed December 24, 1930. Serial No. 504,519.

This invention relates to toy railways.

An object of this invention is to provide increased amusement for the children using

a toy railway by providing a bridge in the track system which may be operated to lift and allow the passage of a train or other movable object under it and returned to normal position in which a train or other movable object may travel over it.

10 In the form at present preferred by reason of its many advantages, the lift bridge is connected in the track system so that the same train may pass alternately under and over it. In connection with this arrangement, one of the salient features of this invention is the provision of means controlled by the arrival of the train at a predetermined point in the system for automatically causing the bridge to be lifted or be re-

15 turned to normal position.

Another of the important features of this invention, particularly in the arrangement just above referred to, is the provision of means controlled by the bridge mechanism for controlling the train so that it will not proceed beyond a predetermined point until the bridge assumes the proper position, and further, so that when the latter occurs the train will continue in its travel either

20 under or over the bridge, as the case may be.

The bridge provided by this invention may be made of materials usually employed in making toys and, of course, includes not only the span but the piers and approaches preferably built as a unitary structure, although, if desired, the span, piers and approaches may be of separable parts to be assembled before use. The span may be arranged to open in any of the ways usual with real bridges, or as desired.

In spite of the wide varieties of its uses and its automatic operating mechanism, the bridge of this invention may be economically made and may be sold at a price in line with prices obtained for electrically operated railways and parts thereof.

Other features and advantages will hereinafter appear.

50 In the accompanying drawings—

Figure 1 is a perspective view of the bridge made in accordance with this invention.

Fig. 2 is a horizontal sectional view showing the manner in which the movable span 55 is guided by the piers.

Fig. 3 is a vertical sectional view showing the actuating means for raising and lowering the bridge and the reversing switch operated by the span when it reaches closed 60 or opened position for rendering the actuating mechanism temporarily inoperative.

Fig. 4 is a diagrammatic view of parts of the actuating mechanism and automatic 65 switches and circuits thereof.

Fig. 5 is a plan view of a toy railway system in which the bridge is placed so as to permit the passage of a train either under or over it.

Fig. 6 is a view like Fig. 1, of a modified 70 form of bridge structure.

Fig. 7 is a plan view showing the manner in which the tracks on the span align with the tracks on the approaches when the bridge 75 is closed.

Fig. 8 is a longitudinal section of the bridge shown in Fig. 6, showing the span in closed position.

The bridge of the present invention shown in Figs. 1 and 3 comprises a base plate 10 80 having piers 11 supported on parts 12 which simulate abutments. Between the piers 11 there is provided a span 13 and leading to the span at each side thereof is an approach 14.

The base 10, abutments 12 and approaches 14 may be formed of one piece of pressed metal and the piers 11 and span 13 may be likewise made of pressed metal formed to simulate girders and cross-pieces similar to those used in real bridge structures. The approaches 14 and span 13 may be arranged to support the usual tracks employed with toy railways, or, as shown, tracks 15 and a third rail 16 may be built in and form a permanent part of the bridge structure.

As stated above, the span 13 of the bridge made in accordance with the present invention is mounted for movement to and from operative position so that a train or other 100

moving object may pass over the bridge or under the bridge as desired. Accordingly, the span 13 in the form of the invention shown in Figs. 1 to 3, is movable relative 5 to the piers 11 so that it may be raised and lowered by actuating mechanism 17, preferably supported by the tops of one or both piers and described in detail below. In the type of bridge shown in Figs. 1 to 3, the 10 span is moved vertically at both ends, although other forms of movable spans may be employed as will hereinafter appear. To guide the span 13 for vertical movement, the girders 18 of the bridge extend between the 15 risers 19 of the piers and slidably engage the same so as to be held against swaying side- wise. The span 13 is also provided with cross-bars 20, one near each end thereof, which slidably engage the inner risers 19 of 20 the piers 11 and prevent endwise swaying movement of the span which, in its preferred form, is connected to the actuating mechanism by cables 21. Hence, it will be seen that the span may be either lowered to 25 the position shown in Fig. 3 or raised to that shown in Fig. 1.

In the broader aspects of this invention, the span 13 may be operated in any suitable way, but preferably the actuating mechanism 30 17 includes an electric motor 22 so that the bridge can be controlled from a remote point and/or automatically. Further, the electric motor may move the bridge in one direction only, allowing it to move in the other direction 35 under the influence of a spring or weight. But again, it is preferable, because of the facility with which the span may thereby be controlled, to have the span move both to and from operative positions 40 by the power applied by the motor 22 which for this purpose may be of the reversible type.

The actuating mechanism may include any suitable form of windlass. In the form 45 shown in Figs. 1 to 3, there are four cables 21, a pair at each end of the span 13 and each pair of cables 21 is wound on drums 23 carried by the shaft 24 having a worm wheel 26 driven by a worm 25 on the motor shaft. 50 Thus, when the proper circuits are closed and the current flows through the motor 22 in one direction, the cables 21 will be wound up on the drums 23 to raise the bridge from the position shown in Fig. 3 to that shown 55 in Fig. 1, and when the circuits are changed to cause the current to flow through the motor 22 in the other direction, the drums 23 are moved in the opposite direction to pay off the cables 21 and allow the bridge to descend 60 to the position shown in Fig. 3.

Preferably, a yielding member such as a spring 27 (see Fig. 3) is inserted between the end of each cable 21 and the span 13 so as to accommodate for an inequality in the 65 lengths of the cables 21 due to stretching

or other causes. It will be noted that there are two actuating mechanisms 17 and two motors 22, one for each end of the span, in the form of the invention being described and illustrated in Figs. 1 to 3. These motors, therefore, should have approximately the same speed of operation so that the span will be lifted evenly at both ends. However, the synchronism between the motors is not at all critical for the arrangement above described for guiding.

The span in the piers is such as to permit a substantial discrepancy between the rising movements of the respective ends of the span. This, coupled with the provision of 70 means in each actuating mechanism for stopping the motor when its end of the span reaches its predetermined closed or opened position, assures the accurate location of the span in these positions.

The means provided for this purpose, in the form of the invention herein disclosed in each actuating mechanism 17, comprises a cable 28 which, except for the insertion of 75 the spring 29 which keeps it taut, is continuous and is guided by eyelets 30 at the top and bottom of one of the piers. This cable 28 extends through an eye 31 in the upper portion of the span 13 and has a pair of buttons 32 and 33 which will not pass through the eye 31. The button 32 is located at the lower end of the cable 28 so as to be struck by the eye 31 as the span 13 approaches its closed position at which time part of the cable carrying the buttons 32 and 33 is pulled down while the button 33 is located at the upper end of the piers so as to be struck by the eye 31 when the span approaches the upper limit of its movement. 80 The cable 28 is connected to a switch 34 which renders the motor inoperative when 85 it is shifted from one position to another.

This switch is a snap switch and has an arm 35 connected to the cable and pivotally mounted on a stud 36 and normally held at 90 the limits of its movement defined by stops 37 by a spring 38. When the cable 28 is pulled, the arm 35 carries the lower end of the spring 38 across the axis of the stud 36 so that the spring will then complete the movement of the arm to bring it against the opposite stop 37. The switch also comprises a disk 39 connected to the arm 35 by a pin-and-slot connection 40 and this disk has contact arms 41 and 42. Hence, when the spring is 95 carried across the axis of oscillation of the arm 35, the disk 39 does not move until the arm reaches a predetermined point whereupon it is picked up and rotated by the arm 100 to shift the contact arms 41 and 42 from engagement with the cooperating contacts which they previously engaged and open 105 the circuit leading to the motor, as will hereinafter appear.

The bridge of the present invention may 110

be used in a toy railway system where the train merely is intended to pass over the bridge while some other movable object is intended to pass under it; but preferably, as indicated in Fig. 5, it may be used in a course of tracks 43 so as to be inserted in one portion thereof and be in train-intercepting relation with another portion thereof. That is to say, the bridge 44 of this invention may be connected to portions 45 and 46 of the course of tracks and in so doing may overlie a portion 47 of the course of tracks which in this case approximates Fig. 8. In this arrangement, it will be observed that the train 48 first passes under the bridge and then over it in the process of which considerable amusement and pleasure is had by the child in observing the movements of the train and the bridge.

In such an arrangement it is preferable and extremely advantageous to have the opening and closing movements of the bridge controlled by the train in its approach toward the bridge either to cross or pass under the same. This is provided for by the present invention, in the form herein shown, by arranging switches 49 and 50 in the course of tracks so as to be engaged and closed by the train. These switches 49 and 50, may, of course, be placed at any appropriate or desired place in the course of tracks—that is, they may be placed as shown in Fig. 5 in position to be operated just after the train has passed over or under the bridge or they may be operated just before the train reaches the bridge to pass over it or under it. In the form shown, the switches 49 and 50 each comprises a blade 51 overlying but insulated from the third rail 16 and in position to be brought into contact with the third rail when the train 48 passes over the point where it is located. These switches 49 and 50 preferably only initiate the operation of the actuating mechanism 17 and hence they are in circuit with contact means 52 which closes the motor circuit upon the momentary engagement of the switch blades 51 with the third rail and keep the motor circuit closed until it is temporarily opened by the switch 34 upon the arrival of the span at either its closed or opened position.

This contact means comprises a pair of electromagnets 53 and 54 each connected to a wire 55 to the switches 49 and 50 respectively, the other sides of the electromagnets being connected by wires 56 to the negative feed wire 57 so that when the switch 49 or 50 is closed current will flow from the positive feed wire 58 through the third rail, switch 49 or 50, wires 55, electromagnet 53 or 54 respectively, wires 56, to the negative feed wire 57. In the contact means shown, there is an armature 59 between the electromagnets 53 and 54 and this armature is not biased to move in either one direction or

another and remains at either electromagnet, according to which was energized last. With the parts in the positions as shown in Fig. 4, the switch 49 controlling the closing of the span 13 was last closed and its associated electromagnet 53 last energized. Hence, the armature 59 lies adjacent the electromagnet 53. Carried by the armature 59 is a contact blade 60 adapted to engage either a contact 61 or a contact 62, depending upon whether the armature 59 is adjacent the electromagnet 53 or 54. The switch blade is connected by a wire 63 leading to a commutator brush 64 of the motor 22 while the contact 61 is connected by a wire 65 to a contact point 66 adapted to be engaged by the contact blade 42 on the reversing switch 34.

The contact 62 is connected by a wire 67 to the contact point 68 adapted to be engaged by the contact blade 41 on the reversing switch 34. The contact arm 41 on the switch is connected to the negative feed wire 57 while the contact arm 42 is connected by a wire 69 to a field 70 of the motor and the latter is connected to the positive feed wire 58. Hence, with the parts shown in the positions indicated in Fig. 4, the switch 49 has been operated to cause the armature 59 to shift to the left and close the circuit including the following—switch blade 60, contact 61, wire 65, contact 66, contact arm 42 on the switch 34, wire 69, field 70 to the positive wire 58, from the negative wire 57 to the contact arm 41, contact 71 engaged thereby, wire 72 to brush 73, through the armature 100 of the motor 22, brush 64, wire 63 back to the switch blade 60, and when the current flows in this direction the motor operates to wind the cable 20 on the drum 23, lifting the span 13 of the bridge. When the span engages the button 33, the arm 35 of the switch 34 is rocked moving the contact arms 41 and 42 away from the contacts 71 and 66 respectively and thus opening the motor circuit to render the motor temporarily inoperative to continue to move the span. In so moving, the contact arms 41 and 42 shift into engagement with contacts 68 and 74 respectively, the latter being connected by a wire 75 to the wire 72 leading to the brush 73 while the former, that is contact 68, is connected by the wire 67 to the contact point 62 which at that time is not engaged by the switch blade 60.

However, when the train 48 engages the switch 50 after passing under the bridge, the electromagnet 54 is energized drawing the armature 59 to the right so that the switch blade 60 engages the contact 62. The circuit thus closed includes the following—contact 62, wire 67, contact 68, contact arm 41 of the switch 34, negative supply wire 57, positive supply wire 58, field 70 of the motor 22, wire 69, contact arm 42 of the switch 34, contact 74, wire 75, wire 72 to the brush 73, 130

through the armature of the motor to the brush 64, wire 63, switch blade 60, back to the contact 62, and this causes the motor to rotate in the direction which will turn the 5 drum 23 so as to unwind the cable 21 therefrom and allow the span 23 to descend until the button 32 is engaged whereupon the snap switch 34 is operated to move the contact arms 41 and 42 back to the contacts 71 and 66 10 respectively, so as to render the motor temporarily inoperative and condition the circuits for the next operation of the track switch 49.

With this arrangement, it is always assured that when the train approaches the 15 bridge in the direction to cross the same, the bridge will be closed and when the train approaches the bridge to pass under the same the bridge will be opened. Should the 20 train be placed on the tracks heading in the direction to cross over the bridge while the bridge is closed, the operation of the track switch 50 will have no effect on the actuating mechanism because the armature 51 was 25 shifted with the contact blade 60 in engagement with the contact 62 in the last operation of closing the bridge.

In order to connect the tracks 15 and third rail 16 carried by the span 13 of the bridge 30 to the like parts in the armature of the system, the tracks and third rail are provided with contacts 76 (see Fig. 3) which are engaged by the tracks and third rail of the span when it is in its closed position.

As stated above, one of the important 35 features of this invention is the provision of means for automatically controlling the train so that the latter will be stopped from attempting to pass over the bridge or under 40 the bridge while the bridge is moving to opened or closed position respectively. This is done by controlling the current supply to the tracks coordinately with the movement of the span 13. In the specific embodiment of this invention shown, this 45 means is designed for use with so-called automatically remote controlled electric engines. These engines are supplied with switch mechanism and an armature or the like which at each interruption of the supply current operates the switch one step. In the usual arrangement, the switch is so 50 arranged that assuming that the train is traveling forwardly, the first interruption of the 55 current in the track circuit causes the switch to move to neutral position at which the train is stopped. The next interruption causes the engine to move in reverse. The next interruption causes the engine to stop, and the next interruption again 60 causes the engine to travel forwardly.

Accordingly, the feed wire 58 leading to the third rail is interrupted and has a gap at 77 across which a pair of switch 65 blades 78 are connected. These switch blades

are normally engaged so as to complete the circuit to the tracks and are held closed by a cam 79 having a gear 80 driven by a pinion 81 on the drum shaft 24. The cam 79 is so geared to the drum that it makes one revolution for a number of revolutions which the drum requires to raise or lower the span 13 and the cam is arranged so that when the span is completely opened and completely closed, the positive supply wire circuit is closed.

While the bridge is still in either closed or opened position, the track supply circuit which includes the switch blades 78 is kept closed by the lobe 82 on the cam 79 which engages a follower 83 on one of the switch arms. When, however, the span is moved away from its normal positions either in opening or closing direction, a dwell 84 on either side of the lobe 82 reaches the follower 83 and allows the circuit to be opened so that the train stops. During the movement of the span, the cam 79 continues to turn and somewhere between its terminal positions three lobes 85 on the cam reach the follower. These lobes momentarily close the track circuit so that the impulses thereby produced will operate the automatic mechanism in the train so that when the lobe 82 again engages the follower at the time the bridge is completely open or completely closed, the train will start up and continue to go in the intended direction.

The first of these three lobes 85 causes the engine of the train to be shifted to neutral, the second causes the engine to be shifted to reverse and start up in reverse direction but, as the contact is only momentary, the engine does not move any substantial distance, the third of these lobes 85 causes the 95 engine to again be shifted to neutral so that when the lobe 82 is reached the engine will start forward.

In the modifications of this invention 100 shown in Figs. 6, 7 and 8, a slightly different form of bridge is shown. In this case, the abutments 11a are joined to an arch 84 containing a single actuating mechanism 17a for lifting both ends of the bridge with a single motor 22. In this form of the invention, the span is guided by guide rods 85 passing through holes 86 in the ends of the span.

While in this instance a single motor 22 is employed to raise and lower the span 13a, it should be understood that the actuating mechanism 17a may be identical with the actuating mechanism 17 in the form of the invention shown in Figs. 1 to 3 in all respects, including the automatic reversing switch 34, the contactor means 53, 59, 54 and the train control means including the contacts 78 and cam 79.

Variations and modifications may be made within the scope of this invention and por-

tions of the improvements may be used without others.

Having thus described the invention, what is claimed as new and for which it is desired to obtain Letters Patent, is:—

1. A toy railway bridge comprising as a unitary portable structure: piers; approaches; and a span movably mounted to permit the passage of movable objects beneath or upon it.

2. A toy railway system having a course of tracks for a toy railway train; a bridge inserted in the course of tracks and including a span movable to closed and opened positions and in the latter forming a gap in the course of tracks; actuating means for moving the bridge to and from closed and opened positions; means in the course of tracks for initiating the operation of the actuating means when the train thereon reaches a predetermined point in approaching the bridge; means operated when the span reaches closed or opened positions for rendering the actuating means inoperative; means operated when the span is between closed and opened positions for stopping the train from continuing to approach the bridge; and means for restoring the train when the bridge reaches closed or open positions.

3. A toy railway system having a course of tracks for a toy railway train; and a bridge structure inserted in the course of tracks and including a movable span adapted to overlie in train-intercepting relation another part of the course of tracks.

4. A toy railway system having a course of tracks for a toy railway train; a bridge structure inserted in the course of tracks and including a movable span adapted to overlie in train-intercepting relation another part of the course of tracks; and actuating means for moving the span to closed position in which the train may pass over the span and to open position in which the train may pass under the span.

5. A toy railway system having a course of tracks for a toy railway train; a bridge structure inserted in the course of tracks and including a movable span adapted to overlie in train-intercepting relation another part of the course of tracks; actuating means for moving the span to closed position in which the train may pass over the span and to open position in which the train may pass under the span; the span in moving to the latter position forming a gap in the course of tracks; and means in the course of tracks for initiating the operation of the actuating means to cause the latter to move the span to closed position when the train on the tracks reaches a predetermined point in approaching the bridge to cross the span.

6. A toy railway system having a course of tracks for a toy railway train; a bridge

structure inserted in the course of tracks and including a movable span adapted to overlie in train-intercepting relation another part of the course of tracks; actuating means for moving the span to closed position in which the train may pass over the span and to open position in which the train may pass under the span, the span in moving to the latter position forming a gap in the course of tracks; means in the course of tracks for initiating the operation of the actuating means to cause the latter to move the span to closed position when the train on the tracks reaches a predetermined position in approaching the bridge to cross the span; means operated coordinately with the movement of the span and operative when the span is traveling toward closed position for stopping the train from continuing to approach the bridge; and means for restarting the train when the span reaches closed position.

7. A toy railway system having a course of tracks for a toy railway train; a bridge structure inserted in the course of tracks and including a movable span adapted to overlie in train-intercepting relation another part of the course of tracks; actuating means for moving the span to closed position in which the train may pass over the span and to open position in which the train may pass under the span, the span in moving to the latter position forming a gap in the course of tracks; means in the course of tracks for initiating the operation of the actuating means to cause the latter to move the span to closed position when the train on the tracks reaches a predetermined point in approaching the bridge to cross the span; and means operated coordinately with the movement of the span and operative when the span is traveling toward closed position for delaying the continued approach of the train toward the bridge until the span is closed.

8. A toy railway system having a course of tracks for a toy railway train; a bridge structure inserted in the course of tracks and including a movable span adapted to overlie in train-intercepting relation another part of the course of tracks; actuating means for moving the span to closed position in which the train may pass over the span and to open position in which the train may pass under the span, the span in moving to the latter position forming a gap in the course of tracks; means in the course of tracks for initiating the operation of the actuating means to cause the latter to move the span to closed position when the train on the tracks reaches a predetermined point in approaching the bridge to cross the span; means operated coordinately with the movement of the span and operative when the span is traveling toward closed position for

delaying the continued approach of the train toward the bridge until the span is closed; and means operated when the span is closed for rendering the actuating mechanism temporarily inoperative.

9. A toy railway system having a course of tracks for a toy railway train; a bridge structure inserted in the course of tracks and including a movable span adapted to 10 overlie in train-intercepting relation another part of the course of tracks; actuating means for moving the span to closed position in which the train may pass over the span and to open position in which the train may pass 15 under the span, the span in moving to the latter position forming a gap in the course of tracks; means in the course of tracks for initiating the operation of the actuating means to cause the latter to move the span 20 to closed position when the train on the tracks reaches a predetermined point in approaching the bridge to cross the span; means operated coordinately with the movement of the span and operative when the 25 span is traveling toward closed position for delaying the continued approach of the train toward the bridge until the span is closed; means operated when the span is closed for rendering the actuating mechanism temporarily 30 inoperative; and means in the course of tracks for initiating the operation of the actuating means to cause the latter to move the span to open position to allow the train to pass under the span when the train approaches the bridge at an intersecting angle. 35
10. A toy railway system having a course of tracks for a toy railway train; a bridge structure inserted in the course of tracks and including a movable span adapted to 40 overlie in train-intercepting relation another part of the course of tracks; actuating means for moving the span to closed position in which the train may pass over the span and to open position in which the train 45 may pass under the span; and automatic means including a switch controlled coordinately with the movement of the span and means in the course of tracks operated by the train approaching the bridge to cross 50 under or over the bridge for causing the span, if open, to close when the train approaches the bridge to cross over the span and to cause the span, if closed, to open when the train approaches the bridge to go 55 under the span.

11. A toy railway system having a course of tracks for a toy railway train; a bridge structure inserted in the course of tracks and including a movable span adapted to 60 overlie in train-intercepting relation another part of the course of tracks; actuating mechanism for moving the span to closed position in which the train may pass over the span and to open position in which the train 65 may pass under the span; and

automatic means including a switch controlled coordinately with the movement of the span and means in the course of tracks operated by the train approaching the bridge to cross under or over the bridge for causing the span, if open, to close when the train approaches the bridge to cross over the span and to cause the span, if closed, to open when the train approaches the bridge to go under the span, and also including a 70 switch device operated coordinately with the movement of the span for delaying the continued approach of the train toward the bridge until the span has either opened or closed according to whether the train approaches the direction to pass under or over the bridge.

12. A toy railway system having a course of tracks for use with toy railway trains having stopping, starting and reversing 85 mechanism controllable from a remote point; a bridge inserted in the course of tracks and including a movable span closing a gap in the course of tracks; actuating means for moving the bridge to and from closed position; and means operated coordinately with the actuating means for causing the train to be stopped, reversed, and stopped again while the bridge is approaching closed position and for causing 90 the train to be restarted when the span reaches closed position.

13. A toy railway system having a course of tracks for use with toy railway trains; a bridge inserted in the course of tracks and 100 including a movable span closing a gap in the course of tracks when in operative position; actuating means for moving the bridge to and from said operative position including an electric motor; and means operated by the train in approaching the bridge for initiating the operation of the actuating means.

14. A toy railway system having a course of tracks for use with toy railway trains; a bridge inserted in the course of tracks and including a movable span closing a gap in the course of tracks when in operative position; actuating means for moving the bridge to and from said operative position including an electric motor; means operated by the train in approaching the bridge for initiating the operation of the actuating means, said means including switches on the tracks; and contactor means associated therewith and the actuating means including a reversing switch whereby the span will be opened and closed alternately as the train alternately reaches and operates the said switches on the tracks.

15. A toy railway system having a course of tracks for use with toy railway trains; a bridge inserted in the course of tracks and including a movable span closing a gap in the course of tracks when in operative posi- 130

- tion; actuating means for moving the bridge to and from said operative position including an electric motor; means operated by the train in approaching the bridge for initiating the operation of the actuating means, said means including switches on the tracks; and contactor means associated therewith and the actuating means including a reversing switch whereby the span will be opened and closed alternately as the train alternately reaches and operates the said switches on the tracks, said reversing switch being controlled by the movement of the span upon its arrival at operative and inoperative positions and being in series with the contactor means so as to open the motor circuit upon the arrival of the span at either operative or inoperative positions.
- 20 16. A toy railway bridge comprising as a portable unitary structure a base; piers secured to the base; a span movable with relation to the piers and base and having rails thereon; and approaches for each end 25 of the span also having rails thereon and adapted to align with the rails on the movable span when the span is closed.
17. A toy railway bridge comprising as a unitary structure, piers; and a span mov- 30 ably mounted on said piers to permit the passage of movable objects beneath or upon it.
18. A bridge structure adapted to be inserted in a course of toy railway tracks, in- 35 cluding a movable span adapted to overlie in train intercepting relation another part of the course of tracks.

Signed at Bridgeport, in the county of Fairfield, and State of Connecticut, this

40 22nd day of December, 1930.

RONALD G. SMITH.
